TROPHY

Nicholas J. de Angelis, New York, N.Y., assignor to
National Aviation Club, Washington, D.C., a corpora-
tion of the District of Columbia

Filed Sept. 5, 1967, Ser. No. 8,491

Term of patent 14 years

(Cl. D29—28)

FIG. 1

FIG. 2

FIG. 3

FIG. 4

FIG. 5

FIGURE 1 is a front elevation of a trophy in accordance with the teachings of this invention;

FIGURE 2 is a side elevation as viewed from the left in FIGURE 1;

FIGURE 3 is a rear elevation;

FIGURE 4 is a side elevation as viewed from the right in FIGURE 1, and

FIGURE 5 is a top plan view of FIGURE 3 as it appears with the broken line showing of the base omitted for convenience of illustration.

The essential features of the design reside in the portions shown in solid lines; a conventional base being shown in broken lines in FIGS. 1-4.

I claim:

The ornamental design for a trophy, as shown and described.
